UNITED STATES PATENT OFFICE.

SIGISMOND G. BOERNSTEIN, OF WASHINGTON, DISTRICT OF COLUMBIA.

ADVERTISING APPARATUS.

1,208,462.

Specification of Letters Patent. Patented Dec. 12, 1916.

Application filed November 3, 1913. Serial No 798,875.

To all whom it may concern:

Be it known that I, SIGISMOND G. BOERNSTEIN, a citizen of the United States, residing at Washington, District of Columbia, 5 have invented certain new and useful Improvements in Advertising Apparatus, of which the following is a specification.

This invention relates jointly to improvements in advertising apparatus and moving 10 picture machines, and has for its primary object the novel production or exhibiting of moving pictures directly on the glass or pane of the show window of a store, whereby the dealer in any class of goods may 15 exhibit his wares in a manner which will be exceedingly attractive and efficient from an advertising standpoint.

A further object of the invention is to provide improved means whereby the apparatus 20 may be expeditiously made to conform to the particular requirements of any given case, as, for example, the size of the show window, the depth thereof, and the consequent required size or area of the field 25 of display of the moving pictures and the distance the projecting machine must be spaced from the glass of the window.

The invention also has for its object improved means or mechanism of this character, the parts of which are so constructed 30 and arranged that they will not occupy or require the entire space of the show window for their operation, but will permit all of the show window, with the exception of a 35 prescribed area, to be utilized for ordinary display purposes.

A still further object of the invention is an advertising apparatus which may be very quickly put up in position for operation in 40 a show window so that the pictures may be projected from the rear and be viewed from the front by the passers-by, the apparatus including a frame which may be easily secured to the rear face of the glass at the 45 front of the window without the necessity of employing visible fastening devices, whereby the attractiveness of the display is added to and without the necessity of permanently securing the frame to the glass, the construction and arrangement of parts providing 50 for the almost instantaneous attachment and detachment of the entire apparatus without the necessity of making any changes in the construction of the show window, and

practically without disturbing any parts 55 thereof.

More specifically considered, the invention has for its aim to provide an extensible cone made up of a plurality of sections adapted to telescope with one another, whereby any 60 desired number of sections may be detached or added to make the cone of the required length, said cone being arranged for detachable connection at one end to a frame which is preferably made up of a plurality 65 of extensible and separate parts provided with means, whereby they may be easily secured to the glass of a show window and extended or contracted, in assembled relation to each other, to produce a field of the 70 required area. And the invention also aims to generally improve devices of this class so as to render them more useful and commercially desirable.

With these and other objects in view, as 75 will more fully appear as the description proceeds, the invention consists in certain constructions, arrangements and combinations of the parts that I shall hereinafter fully describe and claim. 80

For a full understanding of the invention, reference is to be had to the following description and accompanying drawing, in which—

Figure 1 is a side elevation of my device, 85 the view being in the nature of a diagram, with one part in section and one part partly broken away. Fig. 2 is a fragmentary face view of the frame of the apparatus. Fig. 3 is a fragmentary sectional view thereof, 90 and, Fig. 4 is a sectional view of one of the members of the extensible cone.

Corresponding and like parts are referred to in the following description and designated in the accompanying drawing by like 95 reference characters.

Referring to the drawing, the numeral 1 designates the glass front of a show window, 2 the body portion of the show or display window itself, and 3 a picture projecting or moving picture machine which may be of any size or type such as will fulfil the requirements of the case, the moving picture machine being intended to be positioned upon a foldable stand or the like at or in the 100 rear of the show window so as to project the pictures forwardly upon the glass 1. 105

In carrying out my invention, I provide a

preferably rectangular frame 4 made up of separable sections with mitered corner joints, said sections being preferably formed of fiber or some other suitably rigid and light 5 substance or material. Preferably, each of the sections of the frame 4 is formed of extensible parts or members having nesting or telescopic relation with each other as indicated at 4', whereby they may be extended or contracted to produce a frame of 10 the required size. The frame 4 is preferably provided with a relatively soft facing 5 of felt, velvet, rubber or some equivalent substance or material, and each section is 15 provided, preferably near or at its ends, with suction cups 6 of rubber or the like, whereby the entire frame may be easily secured to the rear side of the glass front without being permanently connected there- 20 to and without the employment of any fastening devices which will be visible, to all practical intents and purposes.

If desired, the frame 4 may be formed on its inner edge with a longitudinal groove or 25 rabbet 7 for the reception of a glass, this being desirable in some cases where, for example, the pictures are shown in the center or back of the window; but it is to be understood that my invention is primarily 30 designed for use with the frame 4 directly in contact with the rear face of the window front or glass pane 1, in which event, the separate glass in the groove 7 would be dispensed with.

35 In connection with the frame 4, I use a cone, designated 8 as a whole. This cone may be of any desired shape in cross section, although conforming to the outline of the frame with which it is used, and is prefer- 40 ably also formed of fiber, although it is to be understood that the invention is not limited in this regard. It is made up of any desired number of truncated members or sections 9 arranged for telescopic relation with 45 each other, as clearly illustrated in the drawing, whereby any number of sections may be removed or added, as required, and whereby the entire cone may be "knocked down" for purposes of transportation or shipment. 50 One member of the sectional and telescopic cone 8 is preferably formed with a sight opening 10 in its side, the walls of said opening being obliquely disposed with reference to the longitudinal axis of the cone 55 and being designed to afford the operator at the machine 3, a view of the field which is circumscribed by the frame 4, so that he may at all times, view the field and see to it that the machine is working properly and 60 that the pictures are properly displayed.

Another section of the cone is formed with an outstanding edge flange 11 which is adapted to be engaged by turn buttons 12 or similar readily detachable fastening de- 65 vices carried by the sections of the frame 4,

whereby the cone, at its larger end, may be readily attached to the frame and as readily disconnected therefrom. Preferably, the frame is formed with a laterally extending flange 13, over which the flanged section of the cone is adapted to be slipped, whereby the cone will be properly supported in rigid condition. 70

From the foregoing description in connection with the accompanying drawing, the 75 operation of my improved picture projecting and advertising apparatus will be apparent.

In the practical use of the device, the frame 4 is adjusted to the required size and 80 secured by its suction cups 6, to the rear side or face of the glass front of a show window, for example, and the cone 8 is attached to the frame and extends rearward in a horizontal position therefrom, the cone being 85 lengthened or shortened, as required, and having positioned at its rear or smaller end, the moving picture apparatus or projector 3. Thus, when the machine is set in operation, 90 there will be seen by the passers-by in front of the show window, pictures of living models displaying gowns or cloaks, for example, or pictures of the various steps of the manufacturing operation showing how various goods are made, whereby an attractive advertising means is provided, it being proposed in the preferred manner of operation, 95 to arrange the film in such a manner that the operation will be a continuous one, the series of pictures being repeated as long as 100 desired.

It will be seen that I have provided for this purpose a very simple construction and arrangement of parts which may be readily adjusted, both as to the area of the field and the length of the cone, which may be readily collapsed so as to occupy very little space in being carried from one place to another, and which may be readily set up and expeditiously secured to the glass front of a show 105 window so as to project the pictures from the rear forwardly. It will also be noted that the opaque cone 8 will occupy a comparatively small part of the space in the show window and that the apparatus will in 110 no wise interfere with the remaining space being lighted and employed for the display of any desired articles.

It is to be understood that the portion of the glass front which is bounded by the 115 inner or outer edge of the frame 4 is coated or otherwise prepared in some way as to render it capable of retaining and displaying the pictures projected thereon by the moving picture machine, a substance being 120 preferably employed which may be readily removed when the apparatus is not in use.

While the accompanying drawing illustrates what I believe to be the preferred embodiment of my invention, it is to be under- 130

stood that the invention is not limited thereto, but that various changes may be made in the construction, arrangement and proportions of the parts without departing from 5 the scope of the invention, as defined in the appended claims.

What I claim is:—

1. An advertising apparatus of the character described, including a light confining cone, a frame connected to one end thereof, and means carried by said frame for adhesively connecting the same to a glass. 45
2. An advertising apparatus of the character described, including a light confining cone, a frame connected to one end thereof, and means carried by the frame for causing the latter to adhere to a glass, the frame being formed in its inner edge with a groove, for the purpose specified. 50
3. An advertising apparatus of the character described, including a frame provided with a groove to receive a pane of glass, and suction cups carried by said frame, for the purpose specified. 55
4. An advertising apparatus of the character described, including a frame provided with a flange, a light confining cone provided at one end with a flange and adapted at such end to slip over the flange of the frame, and fasteners carried by the frame for engagement with the flange of the cone, whereby to connect the cone and frame together. 60
5. An advertising apparatus of the character described, including a light confining cone, a frame connected to one end thereof, and means for attaching said frame to a glass, said frame being formed with a relatively soft facing designed to engage the glass. 65
6. An advertising apparatus of the character described, including a light confining cone, a frame connected to one end thereof, and means for attaching said frame to a glass. 70

cone, a frame connected to one end thereof, and means for attaching said frame to a glass.

7. An advertising apparatus of the character described, including a light confining cone, a frame connected to one end thereof, and suction cups carried by said frame, for the purpose specified. 75

8. In an advertising apparatus of the character described, an extensible light confining cone, and an extensible frame connected to one end thereof, for the purpose specified. 80

9. An advertising apparatus of the character described, including a light confining cone, and a frame adapted to be connected to one end thereof, said frame being constructed in a plurality of separable extensible sections. 85

10. An advertising apparatus of the character described, including a light confining cone, consisting of a plurality of separable sections arranged in telescopic relation to each other, and an extensible frame engageable with said cone. 90

11. An advertising apparatus of the character described, a light confining cone, a frame provided with a laterally extending flange over which one end of the cone is adapted to be slipped, the said end of the cone being formed with an outstanding flange, and turn buttons carried by the frame and arranged to engage the flange of the cone to secure the cone and frame together. 95

In testimony whereof I affix my signature in presence of two witnesses.

SIGISMOND G. BOERNSTEIN.
